2 Sheets-Sheet 2

UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed January 28, 1929. Serial No. 335,477.

This invention relates to improvements in railway draft riggings.

One object of the invention is to provide a railway draft rigging including coupler means at opposite ends of the car and cooperating shock absorbing mechanism located at each end of the car, wherein the coupler means has relatively longer travel in buff than in draft, the buffing shocks being communicated from the shock absorbing mechanism at one end of the car to the shock absorbing mechanism at the other end to obtain the relatively longer travel, wherein means is embodied for limiting the maximum extension of the coupler at either end of the car to less than the travel of the same in buff, or a distance permitted in standard railway practice in connection with independently acting shock absorbing mechanisms employed at opposite ends of the car, having equal compression in buff and draft.

Another object of the invention is to provide a railway draft rigging including a coupler and cooperating shock absorbing means at each end of the car and means for transmitting the buffing shocks from the shock absorbing means at one end of the car to the shock absorbing means at the other end thereof, wherein fixed stop means is employed at opposite ends of the car, having stop elements cooperating therewith, each stop element having shouldered engagement with the corresponding fixed stop means to limit movement outwardly of the car, the stop element functioning as an outer stop member for the shock absorbing means at the corresponding end of the car, the stop element being movable inwardly of the car during the inward movement of the corresponding coupler to provide for relatively greater movement of the coupler in buff than in draft.

A further object of the invention is to provide a railway draft rigging of the character indicated in the preceding paragraph, wherein couplers and yokes which are now standard in railway equipment may be employed together with friction or spring shock absorbing means of standard overall dimensions.

A more specific object of the invention is to provide a railway draft rigging including a coupler at each end of the car, a yoke cooperating with each coupler, a front follower and a friction shock absorbing means disposed within each yoke, movable sill members extending from end to end of the car, the sill-members having inner stop lugs adjacent the opposite ends of the car which cooperate with the shock absorbing means, whereby buffing shocks are transmitted from the shock absorbing means at one end of the car to that at the other end, with the result that relatively greater movement in buff than in draft of the coupler at each end of the car is obtained, fixed stop means at each end of the car and a cooperating stop sleeve having shouldered engagement with each fixed stop means cooperating with the corresponding outer follower, each sleeve, together with the cooperating fixed stop means, functioning as an outer stop member to which the draft shocks are transmitted when the coupler at the corresponding end of the car is pulled outwardly and the buffing shocks are transmitted when the coupler at the opposite end of the car is moved inwardly and the shock absorbing means at both ends of the car is compressed, thereby providing a relatively longer stroke of either of the couplers in buff than in draft, each sleeve being movable inwardly of the car to an extent equal at least to the compression stroke of one of the shock absorbing mechanisms, thereby restricting the relative movement of each coupler and the corresponding sleeve to an extent less than the full inward travel of the corresponding coupler in buff, thus limiting the maximum extension of the couplers so as not to exceed the distance accepted as standard in railway practice.

Other and further objects of the invention will more clearly appear from the description and claims hereinafter following.

In the drawings forming a part of this specification, Figure 1 is a top plan view of a portion of the underframe structure of a car, which extends from end to end of the same, illustrating my improvements in connection therewith, the underframe structure

- being shown as centrally broken away in order to accommodate the view to the sheet of the drawings. Figure 2 is a horizontal, longitudinal sectional view of one end of the 5 underframe structure illustrated in Figure 1 and corresponding substantially to the line 2-2 of Figure 3. Figure 3 is a longitudinal, vertical sectional view, corresponding substantially to the line 3-3 of Figure 1.
- 10 And Figures 4 and 5 are vertical, transverse sectional views, corresponding substantially to the lines 4-4 and 5-5 of Figure 3, these views being partly broken away.

In said drawings, 10-10 indicate the front 15 and rear body bolsters of the car underframe structure and 11-11 the end sills. The car is provided with couplers at each end thereof, the same being partly broken away and the shanks thereof being designated by 12-12, 20 each shank having the usual head 13 at the outer end thereof.

In carrying out my invention, I provide body bolsters of special design, as most clearly illustrated in Figures 2, 3 and 5. Each 25 body bolster comprises a top plate 14 extending entirely across the car and secured to the usual side sills, not shown; bottom plates 15-15 extending inwardly from the side sills and secured thereto in the usual manner; dia- 30 phragm plates 16-16 secured to the side plates and top plate; and a central casting 17. The casting 17 has laterally extending hollow sections 18-18 on opposite sides thereof defined by inner vertical wall portions 19-19, spaced side wall portions 20-20 and top and bottom wall portions 21-21. The hollow sections 18 are preferably reinforced by a central vertical web 22 formed integral with the top and bottom walls and 40 the inner end wall 19. As most clearly shown in Figures 2 and 5, the walls 19 are spaced apart for a purpose hereinafter pointed out. The portions 18 of the casting are connected by a relatively thick bottom web 23 formed integral with the bottom wall portions 21. The top wall 21 of each member 18 is downwardly offset, as indicated at 24, thereby providing an opening or guideway between the same and the top plate 14 of the bolster member. At the bottom end, each wall 19 is connected to the bottom wall 21 by a web portion 25 which is offset with respect to the main body portion of the wall 21, thus providing a guideway between the web 25 and 50 said wall similar to the guideway or opening between the wall portion 24 and the top plate 14. At the outer end, each wall 21 is cut away on the bottom side to receive the inner end portion of the corresponding bottom plate 15 which is riveted to said wall. The top walls 21 are also preferably riveted to the top plate 14, as most clearly shown in Figure 5.

The web member 23 is provided with up- 65 standing spaced transverse ribs or walls

26-26, there preferably being four such ribs or walls. Two of the ribs 26 are located at the front and rear edges of the web 17 and the remaining two are disposed closely adjacent each other approximately at the center of said web. The web 23 is provided with the usual center pin receiving opening 27 which accommodates the pin that connects the body and truck bolsters. As shown in Figures 2 and 5, the ribs 26 are connected by web members which define, together with the central portions of said ribs, a tubular upper section, the opening of which is a continuation of the center pin receiving opening of the web 23. The ribs 26 have their opposite ends spaced from the walls 19, thereby providing an opening at each side for a purpose hereinafter pointed out.

The end sill members 11 at the opposite ends of the car are also of special design, each being provided with an opening 28 adapted to accommodate the coupler shank and associated parts of the draft rigging. The opening is defined by a top wall 29, side walls 30-30 and a bottom wall 31 in the form of a detachable plate. The top wall 29 forms in effect a continuation of the top member of the end sill. The side walls 30 are relatively thick and are recessed on the inner sides at the bottom thereof, as indicated at 32-32, to provide pockets or seats adapted to accommodate the opposite sides of the bottom plate 31 so that the bottom face of said plate will be flush with the bottom member of the end sill.

As most clearly shown in Figure 4, the plate 31 is relatively heavy and is reinforced by a plurality of longitudinally extending bottom webs or ribs 33-33. The plate is preferably secured to the end sill by means of vertically disposed bolts 34-34 extending through the sill. The side walls 30 are provided with vertically disposed, opposed, relatively thick ribs 35-35 on the inner sides thereof, the ribs 35 presenting fixed stop shoulders 36 and 37 at the front and rear sides thereof. The end sill is also provided with rearwardly extended, spaced, vertical wall portions 38-38, the outer sides of which are in alignment with the side walls 30. The inner surfaces of the walls 38 are outwardly offset with respect to the side walls, thereby presenting transverse shoulders 39-39 which are in alignment with the rear face of the corresponding end sill. The bottom plate is of such a length that the rear edge thereof is in substantial alignment with the rear ends of the walls 38, as most clearly indicated in Figures 2 and 3.

A pair of channel shaped spaced sills 40-40 are arranged lengthwise of the car, the opposite ends of the same being supported by the plates 31 and are guided between the walls 38-38 of the end sills. The sills 40 pass through the body bolsters of the car and the vertical webs thereof are guided be-

5 between the walls 19 and the outer edges of the ribs 26 of the bolsters, and the top and bottom flanges of each sill are guided in the openings defined by the top plate 14, the offset wall portion 24 and by the bottom wall 21 and the offset wall portion 25 at the corresponding side of each body bolster.

10 The two sills 40 are preferably connected by cover plates 41—41 secured to the top flanges of the sills, tie plates 141—141 and saddle plates 42—42 secured to the bottom flanges. The sills are spaced apart the proper distance to receive a shock absorbing mechanism therebetween, which may be either of 15 the spring or friction type, the mechanism shown in the drawings being of the friction shell type. The front and rear ends of the sills 40 terminate short of the shoulders 39 of the front and rear end sills and are normally centered between said shoulders of the two end sills. In order to strengthen the ends 20 of the sills 40, reinforcing castings 43—43 are employed, the castings having vertically disposed walls fitting the outer faces of the 25 vertical webs of the sills 40, transverse end walls terminating flush with the ends of the sills and top and bottom flanges engaging the inner surfaces of the top and bottom flanges of the sills. The reinforcing castings 30 43 are preferably secured to the sills by riveting, as shown in the drawings. It will be understood that the construction of the sills 40 is the same at both ends of the car and that both ends of the same are reinforced by castings 35 43.

A stop sleeve 44 is employed at each end of the car, the same being disposed in the opening 28 of the corresponding end sill. Each sleeve 44 is preferably of substantially rectangular cross section having spaced vertical side walls and horizontally disposed, spaced top and bottom walls. At the forward end, the side walls of each sleeve are provided with opposed laterally projecting lugs or 45 vertical ribs 45—45 which cooperate with the shoulders 36 to limit the inward movement of the sleeve.

50 Between the ends, the side walls are provided with an additional pair of laterally extending lugs or ribs 46—46 which cooperate with the stop shoulders 37 to limit the outward movement of the sleeve. Each sleeve is also provided with coupler key guide slots 47—47 in the opposed side walls thereof. 55 The side walls of the sleeves 44 are spaced apart such a distance that the sleeves will work freely between the ribs 35 of the end sills, and the lugs 45 and 46 are so designed that they clear the side walls of the openings 60 in said end sills. The front end of each sleeve 44 is normally spaced such a distance from the corresponding coupler head as to permit relative movement of the parts to an extent at least as great as the compression stroke 65 of one of the shock absorbing mechanisms

employed. The sleeve 44 at each end of the car accommodates the corresponding coupler shank and the rear end portion thereof functions as the front stop member for the shock absorbing mechanism at that end of the car. 70 Each coupler shank has a yoke member 60 connected thereto by a key 48 extending through an opening in the coupler shank and aligned guide slots 49—49 in the side arms of the yoke. The yoke 60 is of a well known type and the shock absorbing means, as well as a front main follower 50, is supported therewithin. The shock absorbing means is of the well known friction shell type and includes a friction shell 51, a pair of friction shoes 52—52, a wedge block 53 cooperating with the shoes, the shell containing the usual spring resistance which opposes movement of the parts. The coupler key is of such a length as to extend through the side arms of the yoke and has the opposite ends thereof working in the guide slots 47 of the corresponding sleeve 44.

75 The sills 40 are provided with inner stop lugs 54—54, the same being arranged in sets adjacent the opposite ends thereof and cooperating with the corresponding friction shells 51. The stop lugs 54 are fixed to the sills 40, being preferably secured by rivets, as shown.

80 The normal position of the parts is that shown in the drawings, wherein the shock absorbing mechanisms are in full release and hold the front followers 50 in their outermost position engaged with the inner ends of the sleeves 44 which are held against outward movement by engagement of the lugs 46 thereof with the shoulders 37 of the end sills. The couplers at the opposite ends of the car are also in their fully extended position, having their inner ends bearing on the front followers 50 and being held against outward movement with respect to the yokes 60 by the keys 48 engaging the outer ends of the guide slots 49, the keys thus being held spaced from the opposite ends of the slots 47 in the side walls of the sleeves 44, the same being spaced a greater distance from the outer end walls of said slots than from the inner end walls thereof. The 85 sleeves are held in such a position that the lugs 45 thereof are spaced from the shoulders 46 of the corresponding end sills a distance at least as great as the compression stroke of one of the friction shock absorbing mechanisms and the sills 40 have the opposite ends thereof spaced a similar distance from the shoulders 39 of the end sills.

90 The operation of my improved railway draft rigging, assuming a draft or pulling action being applied to the coupler at either end of the car, is as follows:

95 The coupler, in its outward movement, will pull the corresponding yoke 60 therewith, compressing the friction shock absorbing

mechanism between the inner end of the yoke and the main follower 50, the latter being held in fixed position with respect to the car by engagement with the inner end of the sleeve 44 at that end of the car, the latter being held against outward movement by the lugs 46 thereof engaging the stop shoulders 37 of the end sills. Compression of the friction shock absorbing mechanism will be limited by engagement of the friction shell with the main follower 50. In this connection, it is pointed out that the outward movement of the coupler head with respect to the end of the car and the corresponding sleeve 44 will be equal to the compression stroke of the friction shock absorbing mechanism.

When a buffing action is applied to the coupler at one end of the car, the same will be forced inwardly, thereby forcing the corresponding outer follower 50 inwardly also and compressing the friction shock absorbing mechanism between the outer follower and the stop lugs 54 of the sills 40 at the same end of the car. Inasmuch as the sills 40 are movable, the same will be moved longitudinally of the car during the described action, and the friction shock absorbing mechanism at the other end of the car will be compressed between the stop lugs 54 at that end of the car and the corresponding front or main follower 50 which is held against movement by engagement with the sleeve 44, the lugs 46 of which are held against movement by engagement with the shoulders 37 of the corresponding end sill.

As will be evident, a longer stroke is obtained in a buffing action than is had in draft, because the shock absorbing mechanisms at both ends of the car are compressed during a buffing stroke. During the inward movement of the coupler hereinbefore referred to, the corresponding coupler key will engage the inner end walls of the slots 47 of the corresponding sleeve, thereby forcing the sleeve inwardly also, this movement being permitted by the clearance provided between the lugs 45 of said sleeve and the shoulders 36 of the corresponding end sill. The relative movement between the coupler and the sleeve 44 is thus substantially the same during either a draft or buffing action of the mechanism.

In release, after the railway draft rigging has been subjected to a buffing action, the expansion of the shock absorbing mechanisms at the opposite ends of the car will force the followers 50 outwardly, carrying the couplers outwardly therewith during the first part of the releasing action and then engaging the sleeves 44 and forcing the same outwardly until movement thereof is limited by engagement of the lugs 46 with the shoulders 37 of the end sills, whereupon the followers will be held stationary and the further expansion of the shock absorbing mechanisms will force

the sills 40 to their centered position between the end sills of the car, the centering force being transmitted thereto through the inner stop lugs 54 which cooperate with the shock absorbing mechanisms.

The spacing between the ends of the sills 40 and the shoulders 39 of the end sill at each end of the car is preferably such as to equal the compression stroke of the corresponding shock absorbing mechanism, so that movement of the sills 40 will be arrested at the same time that compression of the corresponding shock absorbing mechanism is limited by engagement of the shell 51 with the outer follower 50, thereby distributing the buffing strains.

Although the inward movement of each coupler during a buffing action is substantially double the movement during a draft action, the spacing of the coupler head with respect to the sleeve and the end of the car will not exceed that allowed in standard railway practice, because the sleeve is movable to the extent of the compression of one of the draft gears during the inward movement of the coupler in buff and the outward movement of the same during release after a buffing action. This is exceedingly important in railway practice, because an excessive extension of the coupler head with respect to the end of the car and the striking casting thereof would endanger the trainman because the extension of the coupler head would be so great as to permit the trainman's foot to get caught and injured when the coupler is moved inwardly during a buffing action.

While I have herein shown and described what I consider the preferred manner of carrying out my invention, the same is merely illustrative and I contemplate all changes and modifications which come within the scope of the claims appended hereto.

I claim:

1. In a draft rigging for railway cars having stop means at each end of the car, the combination with spaced, longitudinally extending sills, said sills being movable lengthwise with respect to the car, said sills being provided with a set of inner stop lugs adjacent each end thereof; of a friction shock absorbing mechanism cooperating with each set of inner stop lugs; a coupler at each end of the car; a yoke operatively connecting each coupler with the friction shock absorbing mechanism at the same end of the car; an outer follower for each friction shock absorbing mechanism; a movable outer stop member for each of said followers having shouldered engagement with the stop means at the corresponding end of the car.

2. In a draft rigging for railway cars having fixed stop means at each end of the car, the combination with a coupler at each end of the car; of a yoke operatively connected to each coupler; a shock absorbing mecha-

nism and a cooperating outer follower within each yoke; a movable stop member at each end of the car interposed between the corresponding outer follower and the fixed stop means, said movable stop member having its outward movement limited by said fixed stop means; and spaced, longitudinally movable sills between which the shock absorbing mechanisms are disposed, said sills having inner stop means thereon cooperating with each of said shock absorbing mechanisms.

3. In a draft rigging for railway cars having fixed stop means at opposite ends thereof, the combination with a coupler at each end of the car; of a shock absorbing means at each end of the car adapted to be compressed upon inward movement of the corresponding coupler during buffing action; pressure transmitting means interposed between the shock absorbing means at opposite ends of the car for transmitting the buffing shocks from one to the other; an outer follower cooperating with each shock absorbing means and engaged and actuated by the coupler in buff; and outer stop members cooperating with each outer follower, said outer stop members having their outward movement limited by said fixed stops, said couplers being movable inwardly of said outer stop members in buff, and said outer stop members being movable inwardly of the car and of said pressure transmitting means during the inward buffing movement of the corresponding coupler.

4. In a draft rigging for railway cars, the combination with fixed stop means at each end of the car; of a coupler at each end of the car; a shock absorbing mechanism at each end of the car; pressure transmitting means movable with respect to the car for transmitting the actuating force from one shock absorbing mechanism to the other; yoke means connecting each coupler with the corresponding shock absorbing mechanism; and a movable outer stop member cooperating with each shock absorbing mechanism and having its outward movement limited by the corresponding fixed stop member, each coupler having movement inwardly of the corresponding stop member in buff and each movable stop member being movable with respect to the pressure transmitting means and also movable inwardly of the car a distance at least equal to the compression stroke of one of said shock absorbing mechanisms.

5. In a draft rigging for railway cars, the combination with fixed stop means at each end of the car; of a coupler at each end of the car; a shock absorbing mechanism cooperating with each coupler; yoke means operatively connecting each coupler and corresponding shock absorbing mechanism; a movable outer stop member at each end of the car interposed between the corresponding shock absorbing mechanism and fixed stop

and having shouldered engagement with said stop to limit outward movement of said member; and means interposed between the shock absorbing mechanisms at opposite ends of the car for transmitting the buffing shocks from one of said mechanisms to the other to provide for a longer stroke of either of said couplers in buff than in draft, each of said outer stop members being movable inwardly of the car during buffing action of the corresponding coupler, whereby the relative movement of said coupler and outer stop member is less than the combined compression strokes of said shock absorbing mechanisms.

6. In a draft rigging for railway cars, the combination with an end sill at each end of the car having stop means thereon; of spaced, longitudinally movable sills, said sills being provided with a set of inner stop lugs adjacent each end thereof; a shock absorbing mechanism cooperating with each set of inner stop lugs, said shock absorbing mechanism including front follower acting means; a coupler at each end of the car directly actuating the corresponding shock absorbing mechanism; a yoke operatively connecting each coupler with the shock absorbing mechanism at the corresponding end of the car to directly actuate the latter in draft; an outer stop member at each end of the car, said stop member being movably mounted with respect to the corresponding end sill and having shouldered engagement with the stop means of said end sill and being engageable by said front follower means of the corresponding shock absorbing mechanism to limit outward movement of said front follower means.

7. In a draft rigging for railway cars having end sills at the front and rear ends thereof, each end sill having fixed stop means thereon, the combination with a coupler at each end of the car; a yoke operatively connected to each coupler; a shock absorbing mechanism and a cooperating front follower within each yoke; a movable stop member at each end of the car interposed between the corresponding outer follower and the fixed stop means of the end sill at the corresponding end of the car and having its outward movement limited by said stop means; and spaced, longitudinally movable sills having inner stop means at opposite ends thereof, cooperating with said shock absorbing mechanisms.

8. In a draft rigging for railway cars having end sills and fixed stop means at each end of the car, the combination with a coupler at each end of the car; a yoke operatively connected to each coupler; a shock absorbing mechanism within each yoke; a movable stop member at each end of the car interposed between the corresponding shock absorbing mechanism and the fixed stop means and having its outward movement limited by said fixed stop means; and spaced, longi-

tudinally movable sills having inner stop means adjacent opposite ends thereof, cooperating respectively with said friction shock absorbing mechanisms, said longitudinally movable sills having their movement limited by engagement with said end sills.

9. In a draft rigging for railway cars having fixed stop means at opposite ends thereof, the combination with a coupler at each end of the car; of shock absorbing means cooperating with each coupler and adapted to be compressed upon inward movement of the corresponding coupler during buffing action; spaced, longitudinally extending sills movable lengthwise of the car, said sills having inner stop means at opposite ends thereof, cooperating with the corresponding shock absorbing mechanism, said sills transferring the buffing forces from one shock absorbing mechanism to the other; outer stop members cooperating with each shock absorbing mechanism, said outer stop members having their outer movement limited by said fixed stops and being movable inwardly of the car during the inward buffing movement of the corresponding coupler; and means at opposite ends of the car for limiting the longitudinal movement of said sills.

10. In a draft rigging for railway cars, the combination with end sills at opposite ends of the car, said end sills each having fixed stop means; of a coupler at each end of the car; a shock absorbing means at each end of the car adapted to be compressed upon inward movement of the corresponding coupler; an outer follower interposed between each shock absorbing means and the corresponding coupler; yoke means connecting said coupler and shock absorbing means to effect compression of the latter when the coupler is moved outwardly in draft; means interposed between the shock absorbing mechanisms at opposite ends of the car for transmitting the buffing shocks from one to the other; and movable outer stop members cooperating with the outer follower of each shock absorbing mechanism, said outer stop members having their outward movement limited by said fixed stop means and being movable inwardly of the car during the inward buffing movement of the corresponding coupler.

11. In a draft rigging for railway cars, the combination with end sills at opposite ends of the car, said end sills each having fixed stop means; of a coupler at each end of the car; a shock absorbing means at each end of the car adapted to be compressed upon inward movement of the corresponding coupler; an outer follower cooperating with each shock absorbing mechanism and engaged and actuated directly by the corresponding coupler in buff; yoke means connecting said coupler and shock absorbing means to effect compression of the latter when the coupler

is moved outwardly in draft; spaced, longitudinally extending sills movable lengthwise of the car, said sills having inner stop means adjacent the opposite ends thereof cooperating with the corresponding shock absorbing mechanisms, said sills transmitting buffing strains from one shock absorbing mechanism to the other; outer stop members cooperating with the follower of each shock absorbing mechanism, said outer stop members having their outward movement limited by said fixed stop means and being movable inwardly of the car and with reference to said movable sills during the inward buffing movement of the corresponding coupler; and means at opposite ends of the car for limiting the movement of said longitudinally movable sills.

12. In a draft rigging for railway cars having fixed stop means at opposite ends thereof, the combination with a coupler at each end of the car; of a shock absorbing mechanism at each end of the car; means for connecting each coupler and shock absorbing mechanism to actuate the same in draft; pressure transmitting means interposed between said shock absorbing mechanisms at opposite ends of the car for transmitting the buffing strain from one mechanism to the other; an outer stop sleeve cooperating with each shock absorbing mechanism, said sleeves engaging said fixed stops to limit outward movement of said sleeves and being movable with respect to said pressure transmitting means, and being also movable inwardly of the car during an inward buffing movement of the corresponding coupler, each of said sleeves accommodating the inner end of the shank of the corresponding coupler.

13. In a railway draft rigging, the combination with fixed end sills at opposite ends of the car, each having stop means thereon; of a coupler at each end of the car; a shock absorbing mechanism at each end of the car adapted to be compressed upon inward movement of the corresponding coupler; yoke means connecting each coupler and the corresponding shock absorbing mechanism to effect compression of the latter when the coupler is pulled outwardly during draft; pressure transmitting means interposed between the shock absorbing mechanism at opposite ends of the car for transmitting the buffing shocks from one to the other; an outer stop sleeve cooperating with each shock absorbing mechanism and adapted to accommodate the inner end of the corresponding coupler shank, said stop sleeves engaging with and having their outward movement limited by said fixed stop means being movable with respect to said pressure transmitting means and also movable inwardly of the car during the inward buffing movement of the corresponding coupler.

14. In a railway draft rigging, the combi-

nation with fixed end sills at opposite ends of the car, each having stop means thereon; of a coupler at each end of the car; a shock absorbing mechanism at each end of the car
 5 adapted to be compressed upon inward movement of the corresponding coupler; yoke means connecting each coupler and the corresponding shock absorbing mechanism to effect compression of the latter when the coupler is pulled outwardly during draft; spaced sills extending lengthwise of the car and having inner stop means adjacent opposite ends thereof, cooperating with said shock absorbing mechanisms, said sills having limited
 10 movement longitudinally of the car, said movement being limited by engagement with the end sills; and an outer stop sleeve cooperating with each shock absorbing mechanism and adapted to accommodate the inner
 15 end of the corresponding coupler shank, said stop sleeves having their outward movement limited by said fixed stop means and being movable inwardly of the car during the inward buffing movement of the corresponding coupler.
 20

15. In a draft rigging for railway cars having end sills at the front and rear ends thereof, the combination with a coupler at each end of the car; a shock absorbing mechanism cooperating with each coupler; yoke means connected to each coupler and having the shock absorbing means disposed therewithin; outer stop means at each end of the car cooperating with said shock absorbing
 30 mechanism, said outer stop means comprising a movable sleeve accommodating the front end of the yoke and the inner end of the coupler shank and having its outward movement limited by engagement with the corresponding end sill; longitudinally disposed spaced sills between which said shock absorbing mechanisms and yoke means are disposed, said sills being movable lengthwise of the car; and inner stop members at adjacent opposite ends of the last named sills and cooperating with the shock absorbing mechanisms at opposite ends of the car, said inner stop members being fixed to said sills.
 40

16. In a railway draft rigging, the combination with a coupler having longer movement in buff than in draft; of shock absorbing means cooperating with said coupler in both buff and draft, said shock absorbing means including a front follower; yoke means
 50 connected to said coupler and enclosing said shock absorbing means; front stop means including a movable sleeve accommodating the shank of the coupler and supporting the shank outwardly of the connection thereof
 55 with the yoke, said sleeve being engaged by said front follower to limit outward movement of said follower, said sleeve having shouldered engagement with fixed stop means on the car to limit outward movement of said
 60 sleeve, said sleeve being movable inwardly of
 65

the car to an extent at least as great as the draft stroke of the coupler and said coupler being movable inwardly with respect to the sleeve during buffing action.

17. In a railway draft riging for cars, the combination with an end sill having an opening; of a stop sleeve movably supported in said opening; cooperating means on said end sill and stop sleeve for limiting both the inward and outward movement of said sleeve; a coupler having the shank thereof disposed within said sleeve; a shock absorbing mechanism cooperating with the coupler; and yoke means connecting the coupler to the shock absorbing mechanism, said yoke means extending into said sleeve.
 70

18. In a railway draft rigging, the combination with an end sill having an opening therein, said end sill having fixed stop means thereon disposed within said opening; of a movable sleeve disposed within said opening and having shouldered engagement with said stop means to limit outward movement of the same; a shock absorbing mechanism; a coupler; a yoke operatively connecting the
 80 coupler and shock absorbing mechanism; and an outer follower interposed between the shock absorbing mechanism and the inner end of the sleeve, said sleeve functioning as outer stop means for the follower.
 85

19. In a railway draft rigging, the combination with an end sill having an opening therethrough; of a movable stop sleeve disposed in said opening, said stop sleeve having shouldered engagement with the end sill to limit outward movement of the sleeve; a shock absorbing mechanism; a coupler; a yoke within which said shock absorbing mechanism is disposed; and a key connecting the yoke and coupler, said key being movable inwardly of the yoke, said sleeve being provided with guide slots receiving the opposite ends of the coupler key, said key engaging the inner end walls of said slots after a predetermined relative movement of the coupler and sleeve to effect inward movement of the sleeve in unison with the coupler.
 90

In witness that I claim the foregoing I have hereunto subscribed my name this 24th day of January, 1929.

JOHN F. O'CONNOR.
